MOBILE CARRIAGE FOR TRIPOD GUN MOUNTS

Samuel G. Green, Alexandria, Va., and Walter H. D'Ardenne, Jenkintown Manor, William J. Meinel, Huntington Valley, and Weber Devore, Horsham Township, Montgomery County, Pa., assignors, by direct and mesne assignments, to Heintz Manufacturing Company, Philadelphia, Pa., a corporation of Pennsylvania

Original application December 31, 1943, Serial No. 516,520. Divided and this application May 23, 1946, Serial No. 671,876

4 Claims. (Cl. 89—40)

1

This application is a division of copending application, Serial No. 516,520, filed December 31, 1943, which issued as Patent No. 2,404,958 on July 30, 1946.

The invention relates to a mobile gun support, and more particularly to a mobile support to which a gun mount may be quickly and easily attached or detached.

A primary object of the invention is to provide a support of the type referred to above.

Another object of the invention is to provide a mobile support for gun mounts of the tripod type in which the legs of the tripod are removable. The invention includes means for attaching removable legs to the mobile support to reduce the size of the mount to a minimum during transportation of the mount on the mobile support.

A further object of the invention is to provide a mobile gun support which may be quickly and cheaply manufactured from readily available materials and which is thereby well adapted to mass production.

These and other objects of the invention will be apparent from the following specification and the accompanying drawings, in which:

Figure 1 is a side elevational view of a wheeled support made in accordance with the invention;

Figure 2 is a top plan view of the support shown in Figure 1;

Figure 3 is a detail side elevational view showing the attachment of the gun mount to the support;

Figure 4 is a detail side elevational view of a quick acting clamp utilized to maintain the gun mount in position on the support;

Figure 5 is a detail front elevational view of the clamp shown in Figure 4;

Figure 6 is a side elevational view of the gun stand shown in Figures 1-3;

Figure 7 is a cross sectional view taken on line 7—7 of Figure 6;

Figure 8 is a top plan view of the stand shown in Figures 1-3; and

Figure 9 is a cross sectional view taken on line 8—8 of Figure 2.

In the preferred embodiment of the invention shown in the drawings, a vertical pedestal support or stand 1 having detachable supporting legs 2 forming a tripod, is adapted to support a gun 3 movable in train and elevation relative to the stand 1.

The stand 1 is comprised of a tubular member 15, the lower end of which is provided with a circular base plate 16. Disposed circumferentially around the lower end of the tubular member 15 and welded to it and to the base plate 16

are three socket or leg housing members 17 adapted to receive the inner ends of the tubular legs 2.

The inner ends of the tubular legs 2 are adapted to be clamped in the leg housing members 17 by means of the clamping arrangement shown in Figure 7. This arrangement is comprised of two clamping jaws 18 and 19 disposed on a shaft 20 passing through transverse openings in the leg housing member 17. One end of the shaft 20 is threaded through the clamping jaw 19 and a threaded locking collar 21 and locking pin 22 keep the jaw from disengaging from the shaft. The other end of the shaft 20 is provided with a pivoted handle 23 which can be adjusted to permit operation in a limited space to turn the shaft 20. The lower surface of the jaws 18 and 19 are flat and have sliding arrangement with a transverse flat bar 24 rigid with the leg housing member 17.

It will be noted that turning of handle 23 in one direction will turn the shaft 20, thus causing the jaws 18 and 19 to be drawn together to clamp the leg 2 in the leg housing member. Operation of handle 23 in the other direction will move the jaws apart, thus unclamping the leg 2. Such a clamping means provides a quick, accurate and simple mechanism for clamping and unclamping the legs.

The mobile support for the mount is comprised of a triangular framework preferably of tubular material. The framework includes a tubular axle support 300 for the wheels 302, 304. Secured to the axle support 300 are two forwardly extending tubular members 306, 308 which are joined at their outer ends to each other and to a metal ring 310 adapted for hooking the wheeled support to a truck, jeep or other prime mover. The tubular members 306, 308 are braced by a tubular cross member 312, and a tubular strut 313 connects this cross member 312 to the axle support.

Near the forward end of the framework is a downwardly depending U-shaped member 314, the upper ends of which are joined as at 316, 318, respectively, to the tubular members 306, 308. Another tubular member 320 is connected at its lower end to the intermediate portion of the base of the U-shaped member 314 and extends forwardly and upwardly with its other end joined as at 322 to the forward ends of the members 306, 308 at the point where they are secured to the ring 310. The U-shaped member 314 and the tubular member 320 comprise a support as will be apparent from Figure 1. The tubular members 306, 308, near their forward ends, carry a

transverse pipe or rod 324 which enables the wheeled support to be drawn by hand when necessary.

The pedestal support of the gun mount is supported on the wheeled support by means of a circular plate 326 which is welded or otherwise secured to the upper surfaces of the axle support 300 and the strut 313. The circular plate carries two hooked lugs 328a, 330a as shown in Fig. 9 to aid in centering the base plate 16 of the mount on the circular plate 326.

The base plate 16 of the mount is held on the circular plate 326 by means of the quick acting clamps shown in detail in Figures 4 and 5. Each clamp is provided with a foot 116 flush with the lower surface of circular plate 326. The foot 116 carries a stud 117 threaded into the plate 326. The upper end of stud 117 is adapted to enter a hole 117a in the base plate 16 of the mount.

The foot 116 is pivotally secured between a pair of links 118, 118' as at 119. The foot 116 is bifurcated at its upper end where it is pivotally connected as at 120 to the arm 121. The other end of arm 121 is pivoted as at 122 in the bifurcated lower end of handle 123. Handle 123 is disposed between the links 118, 118' to which it is pivotally secured by pin 124.

Finally, the links 118, 118' and the handle 123 are provided with holes adapted to align when the device is in clamped position so that a locking pin 125 may be inserted. It will be noted that the arm 121 carries an adjustable bolt 126 the lower end of which engages the upper surface of circular plate 16 of the mount when the device is in clamping position shown in Figure 4. To release the clamp it is only necessary to remove the locking pin 125 and then move the handle 123 to the right (in Figure 4) which will result in raising arm 121 and bolt 126 in an arc out of engagement with circular plate 16 of the mount.

The clamps are to be positioned on plate 16 at holes 117a which are shown in Fig. 2.

When the mount is secured on the wheeled support two of the legs 2' and 2'' of the mount are removed and means are provided for securing all three of the legs while the mount is being transported.

These means for securing the legs include a V-shaped bracket 328 on the member 320 for receiving the vertical web 330 of the center leg 2 as shown in Figure 1. The center leg at its other end remains in its socket in the pedestal support of the gun mount.

The other two legs 2' and 2'' are removed from their sockets (position shown in broken lines in Figure 2) and disposed in their carrying position (shown in full lines). In this position they have been rotated about their longitudinal axes 90°. They rest at their outer ends on the center leg 2. The member 320 has another V-shaped bracket 332 which receives the feet 334, 334' of each of the legs 2' and 2''. The vertical webs 330' and 330'' (now in substantially horizontal position) are disposed beneath the bracket 332 which prevents the outer ends of the legs 2' and 2'' from moving upwardly. The other ends of the legs 2' and 2'' are releasably held by the spring clips 336, 338, respectively, which are secured on small plates 340 welded to the members 306, 308 and 312. Finally, a pair of rectangular supports 342 welded to or otherwise secured to the axle support 300 and the members 306, 308, are provided for carrying the ammunition chests 344.

It will be manifest that the arrangement de-

scribed permits the quick and facile transportation of gun mounts and the rapid assembly of such mount upon reaching a location from which the mounts are to be fired. The support is of such stability that the gun can be fired without removing the mount from the support if required.

While a preferred embodiment of the invention has been illustrated and described, it is to be understood that changes in structure and arrangement may be made without departing from the inventive concepts which are only to be limited to the extent defined in the following claims.

What is claimed is:

15. 1. A gun mount having an upright standard with a base plate and detachable tripod legs socketed adjacent the base plate, a two wheeled carriage support including a triangular frame, a supporting plate carried by said frame, clamping means for detachably securing said base plate to said supporting plate, and means on said frame for securely supporting said legs within the confines of said triangular frame when the device is being wheeled.
20. 2. A mobile carriage for tripod gun mounts having removable legs, said carriage comprising a substantially triangular frame, a pair of wheels carried by one side of said frame, means adjacent the juncture of the other two sides of said frame for supporting that portion of the frame above the ground when the carriage is at rest, means for detachably mounting a gun mount over said wheel carrying side of the frame approximately midway between said wheels, and, means on said frame and said supporting means for securing the legs of a gun mount within the boundaries of said frame, said last named means comprising a pair of V-shaped brackets mounted on said supporting means for engaging the foot ends of the legs, and clips carried by the frame for holding the other ends of at least two of the legs of the mounts.

30. 3. A mobile carriage for tripod gun mounts having removable legs, said carriage comprising a substantially triangular frame, a pair of wheels carried by one side of the frame, means adjacent the juncture of the other two sides of the frame for supporting that portion of the frame above the ground when the carriage is at rest, a plate attached to said wheel carrying side of the frame approximately midway between said wheels for supporting the gun mount, and means carried by said frame and supporting means for securing at least some of said legs, when disassociated from said gun mount, within the boundaries of the frame, said last named means including means within said supporting means for engaging the foot ends of said legs, and means carried by the frame for holding the other ends of at least two of the legs of the mount.

45. 4. A mobile carriage for tripod gun mounts having removable legs, said carriage comprising a substantially triangular frame, a pair of wheels carried by one side of said frame, means for detachably mounting a gun mount over said wheel carrying side of the frame approximately midway between the wheels and means of said frame for securing at least some of said legs when disassociated from said gun mount, within the boundaries of said frame.
